UNITED STATES PATENT OFFICE.

BERNARD R. ANDREWS, OF BRAINTREE, MASSACHUSETTS.

HEAT-INSULATING-WALL CONSTRUCTION.

Application filed January 9, 1922. Serial No. 527,818.

To all whom it may concern:

Be it known that I, BERNARD R. ANDREWS, a citizen of the United States, and resident of Braintree, county of Norfolk, State of Massachusetts, have invented an Improvement in Heat-Insulating-Wall Constructions, of which the following description, in connection with the accompanying drawing, is a specification, like characters on the drawing representing like parts.

This invention relates to walls for buildings and rooms of the type which are designed to resist the passage through them of heat.

15 Walls of this type are used in various buildings where it is necessary to maintain within the building or room a temperature either considerably higher or lower than that of the atmosphere.

20 One use to which walls of this nature may be put is in the building of dry houses or dry rooms wherein it is necessary to maintain a relatively high temperature to perform the drying operation. Such walls are 25 also used in refrigerating rooms or buildings where it is desirable to maintain within the room or building a temperature considerably lower than the outside temperature.

30 It is the object of my present invention to provide a novel heat insulating wall which is simple in construction and inexpensive to manufacture, and which is extremely efficient in preventing the passage 35 of heat therethrough.

In carrying out my invention I make use of the fact that sheet metal having a bright reflecting surface will radiate or transmit or give off heat to the atmosphere very 40 slowly, and in the preferred embodiment of the invention I build the wall with a supporting portion, which may conveniently be of wood, and employ one or more layers of sheet metal having a bright, surface which 45 line the wall but are spaced therefrom thereby providing an air space between the sheet metal and the supporting portion. This air space constitutes a good insulation against heat and the presence of the bright 50 sheet metal surfaces make a wall which has extremely good heat insulating properties.

55 My invention also contemplates the provision of a panel construction suitable for use in a wall of this type, such panel being formed with two separated sides each having a bright surface and enclosing an air

space so that the panel involves an air space enclosed by bright reflecting surfaces. Panels of this construction can be readily manufactured in a factory and then shipped 60 to the place where the wall is to be erected and there assembled.

In order to give an understanding of the invention I have illustrated in the drawings a selected embodiment of the invention 65 which will now be described after which the novel features will be pointed out in the appended claims.

Fig. 1 is a side view of a wall embodying my invention with a portion broken out. 70

Fig. 2 is a section on the line 2—2, Fig. 1.

Fig. 3 is an enlarged perspective view of one of the sheet metal panels.

In the wall herein shown 1 indicates the supporting portion which may conveniently 75 be made of wood, and one convenient way of building this part of the wall is to erect suitable studding 2 on which the boards 3 are sustained. If it is desirable to place the boards 3 vertically then I propose to use 80 cross members 4 between the studding, thus producing a sort of panelled structure as best seen in Fig. 1. The boards 3 may then be nailed to the cross members 4.

The wall also embodies a lining made of 85 sheet metal having a bright surface and this lining may conveniently be secured to the studding 2 and cross members 4. One convenient way of making this lining is to build it in the form of panels 15 which are of 90 a size to fill the space enclosed by two adjacent studs 2 and two adjacent cross members 4.

I will preferably make each panel with two sides separated from each other, each of 95 the sides being of sheet metal having bright surfaces.

One way of making these panels would be to take a piece of sheet metal of that character, such for instance as sheet tin, 100 which as it is manufactured presents a relatively bright and smooth reflecting surface. A piece of sheet metal of this character can then be operated on by a die or otherwise so that one portion thereof will 105 be upset as shown at 6 and then the sheet may be folded back on itself as for instance along the line 5. This will make a panel comprising the two sections 7 and 8, the section 7 being plain and the section 8 being upset as shown at 6. Such a panel will 110 also have the peripheral flange 10 and the

two sections 7 and 8 will be separated from each other to the extent of the depth of the shoulder 6. Such a panel will have a flange or thin portion 6 entirely surrounding it and the space 13 between the walls 7 and 8 will form a dead air space, the sides of which are formed of bright reflecting surfaces.

Panels made in this way can conveniently be secured in place by nailing them to the studding and cross pieces 4 by means of suitable nails 11, it being understood that the flange 10 of each panel will be provided with nail holes 12 through which the nails may be driven. Where the panels are made of a size to fit the spaces enclosed by the studding 2 and cross pieces 4 the separate panel sections can be quickly and rapidly put in place after the body portion of the wall has been erected.

Owing to the bright surfaces of the walls 7 and 8 each section will transmit heat to the air relatively slowly and as a result the amount of heat which is transmitted in a given time through a wall such as herein illustrated is extremely small.

If the wall is used in a dry house or dry room I will preferably place the portion of the wall having a sheet metal lining on the interior of the house or room. In this case the temperature on the metal-lined side of the wall is higher than that on the opposite side. The bright surface of the inner face of the section 7 of the wall prevents to a large extent the transmission of heat from the wall 7 into the space 13 between the sections 7 and 8, and the bright surface of the outside face of the section 8 prevents to a large extent the transmission of any heat from the space 13 to the space 14 between the wall sections 8 and the wooden-supporting portion 1. This wooden supporting portion also has a certain degree of heat insulation so that the total amount of heat which is finally transmitted through the wall in a given length of time is extremely small.

The same result would follow if the temperature on the metal lined side of the wall was considerably lower than the outside temperature. The wall is very simple and inexpensive to manufacture and has extremely high heat insulating properties.

While I have illustrated herein one embodiment of my invention I do not wish to be limited to the constructional details shown.

I claim.

1. A heat insulating wall comprising vertical studs, sheathing secured to the studs, panels also secured to the studs, each panel having a hollow body portion and being made of sheet metal having the natural bright reflecting surface with which it is manufactured.

2. As an article of manufacture, a panel for use in a heat insulating wall, said panel being composed of two metal sheets spaced from each other except at the peripheral portion where they are in contact, the separated walls of the panel presenting bright reflecting surfaces.

3. A heat insulating wall comprising vertical studs, cross pieces between the studs and sheathing supported by the studs, cross pieces, and sheet metal panel sections secured to the studs and cross pieces, each panel section presenting two sheet metal sides spaced from each other and spaced from the sheathing, said sheet metal sides having bright surfaces.

4. As an article of manufacture, a panel for use in a heat insulating wall, said panel being formed of sheet metal having its natural bright reflecting surface and being formed with a peripheral flange and a body portion presenting two separated walls which enclose an air space, the bright reflecting surface co-operating with the air space to increase the heat insulation.

In testimony whereof, I have signed my name to this specification.

BERNARD R. ANDREWS.

two sections 7 and 8 will be separated from each other to the extent of the depth of the shoulder 6. Such a panel will have a flange or thin portion 6 entirely surrounding it and the space 13 between the walls 7 and 8 will form a dead air space, the sides of which are formed of bright reflecting surfaces.

Panels made in this way can conveniently 10 be secured in place by nailing them to the studding and cross pieces 4 by means of suitable nails 11, it being understood that the flange 10 of each panel will be provided with nail holes 12 through which the nails 15 may be driven. Where the panels are made of a size to fit the spaces enclosed by the studding 2 and cross pieces 4 the separate panel sections can be quickly and rapidly 20 put in place after the body portion of the wall has been erected.

Owing to the bright surfaces of the walls 7 and 8 each section will transmit heat to the air relatively slowly and as a result the amount of heat which is transmitted in a 25 given time through a wall such as herein illustrated is extremely small.

If the wall is used in a dry house or 30 dry room I will preferably place the portion of the wall having a sheet metal lining on the interior of the house or room. In this case the temperature on the metal-lined side of the wall is higher than that on the opposite side. The bright surface of the inner face of the section 7 of the wall prevents to a large extent the transmission of 35 heat from the wall 7 into the space 13 between the sections 7 and 8, and the bright surface of the outside face of the section 8 prevents to a large extent the transmission 40 of any heat from the space 13 to the space 14 between the wall sections 8 and the wooden-supporting portion 1. This wooden supporting portion also has a certain degree 45 of heat insulation so that the total amount of heat which is finally transmitted through the wall in a given length of time is extremely small.

The same result would follow if the temperature on the metal lined side of the wall was considerably lower than the outside temperature. The wall is very simple and inexpensive to manufacture and has extremely high heat insulating properties. 50

While I have illustrated herein one embodiment of my invention I do not wish to 55 be limited to the constructional details shown.

I claim.

1. A heat insulating wall comprising vertical studs, sheathing secured to the studs, 60 panels also secured to the studs, each panel having a hollow body portion and being made of sheet metal having the natural bright reflecting surface with which it is manufactured. 65

2. As an article of manufacture, a panel for use in a heat insulating wall, said panel being composed of two metal sheets spaced from each other except at the peripheral portion where they are in contact, the separated walls of the panel presenting bright 70 reflecting surfaces.

3. A heat insulating wall comprising vertical studs, cross pieces between the studs and sheathing supported by the studs, cross 75 pieces, and sheet metal panel sections secured to the studs and cross pieces, each panel section presenting two sheet metal sides spaced from each other and spaced from the sheathing, said sheet metal sides having 80 bright surfaces.

4. As an article of manufacture, a panel for use in a heat insulating wall, said panel being formed of sheet metal having its natural bright reflecting surface and being 85 formed with a peripheral flange and a body portion presenting two separated walls which enclose an air space, the bright reflecting surface co-operating with the air space to increase the heat insulation. 90

In testimony whereof, I have signed my name to this specification.

BERNARD R. ANDREWS.

Certificate of Correction.

It is hereby certified that in Letters Patent No. 1,522,708, granted January 13, 1925, upon the application of Bernard R. Andrews, of Braintree, Massachusetts, for an improvement in "Heat-Insulating-Wall Constructions," errors appear in the printed specification requiring correction as follows: Page 2, line 62, claim 1, for the misspelled word "holow" read *hollow*; same page, line 75, claim 3, strike out the word "and" and insert the same in place of the comma after the word "studs" in the same line, and line 78, for the word "side" read *sides*; and that the said Letters Patent should be read with these corrections therein that the same may conform to the record of the case in the Patent Office.

Signed and sealed this 17th day of February, A. D. 1925.

[*Seal.*]

KARL FENNING,
Acting Commissioner of Patents.
